GARMENT PRESS

William Strobridge, Syracuse, N. Y., assignor to
United States Hoffman Machinery Corporation,
New York, N. Y., a corporation of Delaware

Application October 9, 1940, Serial No. 360,493

4 Claims. (Cl. 38—36)

This invention relates to garment presses of the lever type and particularly to a linkage capable of hand actuation to develop the pressing force. In this linkage the actuating handle has a simple curved closing path and an identical opening path such that the operator merely pulls a single handle down to close the press and lock it under pressure, and pushes the handle up to unlock and open the press.

The resulting single motion actuation is quick and convenient and the path of the actuating handle is close to and consonant with the path of the head on which the handle is mounted. Consequently the entire force is usefully applied. The operator need not move from his normal position at the front of the press. Foot pedals and latches for operating the press are not needed, with the result that considerable simplification of structure and reduction of weight are possible.

A preferred embodiment of the invention will now be described by reference to the accompanying drawings, in which:

Figure 1 is a side elevation of the press in closed position, part of the supporting framework being broken away to show the actuating linkage.

Fig. 2 is a similar view showing the press in open position.

Fig. 3 is a plan view of the press with the parts in the position of Fig. 1; and

Fig. 4 is a perspective view of the linkage and a portion of the mechanism for adjusting the pressure developed between the head and buck when the press is closed.

A portion of the base of the press is indicated generally by the numeral 6. This has a pair of similar upward extensions 7 at the rear of the frame, and spaced apart to receive between them the head lever and the actuating linkage. On the base 6 a table 8 is provided and rising above this table is a pedestal 9 on which a buck 11 of known form is mounted.

Extending horizontally between the upward extensions 7 of the frame 6 is a shaft 12 on which is mounted the head lever structure. This comprises two side members 13 spaced apart and provided with bosses 14 which turn on the cross shaft 12. The side members 13 are connected at their front ends by a cross member 15. Connection with the head 16 is made by means of pads 17 which are bolted to the head. The head 16 coacts with the buck 11 in the usual manner and the head and buck may be equipped with heating means, steaming means, suction means of the vacuum type, and other mechanism not shown in detail but familiar in the press art. Such fea-

tures are not involved in the design of the lever mechanism here under consideration.

At the extreme rear end, the side members 13 are provided with bosses 18 which are aligned and which are connected by a cross shaft 19. There is also a cross connection 21 to which are adjustably attached the two counter-balancing springs 22. The lower ends of these springs are attached to the base 6, the connection being indicated at 23 in Figs. 1 and 2.

Journaled on the cross shaft 19 is the hub 24 of a bell crank whose short, approximately horizontal arm 25 carries a fulcrum pin 26 for one of the main toggle levers. The fulcrum pin 26 is adjustable vertically relatively to the head lever by rocking the bell crank. This rocking adjustment is effected by connecting the upper end of the arm 27 of the bell crank to the clevis 28. In this clevis is threaded one end of a tension rod 29 whose other end is swiveled in the lug 31. A hand wheel 32 and bevel gears 33 provide means for rotating the rod 29 to screw it into or out of the clevis and thus modify the adjustment of the arm 27 and consequently the position of the fulcrum pin 26 relatively to the head lever.

Mounted on the fulcrum pin 26 is the upper toggle lever 34 which is in the form of a bell crank. The lower end of the lever 34 is connected by hinge pin 35 with the second main toggle lever 36. This in turn is mounted on a cross shaft 37 rigidly supported in the frame 6. The link 39 carries a lug 38 which, as the press reaches open position, strikes a hydraulic buffer 39 mounted on the frame 6 and thus limits the opening movement of the press.

To actuate the main toggle, force is applied to the upper arm of the bell crank 34. A handle frame of generally triangular form when viewed in plan (see Fig. 3) is connected by the pivot pin 41 with the upper arm of lever 34. The triangular frame comprises side members 42 connected at their forward ends by the handle 43. About one-third of the distance from the handle to the pin 41 there is a cross frame 44 which stiffens the triangular frame and reinforces it where it supports two aligned trunnions 45, which serve as fulcrum pins.

Journaled on these fulcrum pins are the guide links 46 whose other ends are journaled on aligned fulcrum pins which take the form of trunnions 47 projecting inward from the side members 13 of the head lever. A lug 48 carried on cross frame 44 collides with a buffer 49 carried on the cross member 15 on the head lever and thus arrests the motion of the handle 43,

the point of arrest being such that the secondary toggle formed by links 46 and the members 42 will move to or very slightly past dead center and lock before motion is arrested. At such time the fulcrum pins or trunnions 45 have moved to or slightly past alignment with the fulcrum pins or trunnions 47 and the pin 41, as shown in Fig. 1.

To close the press it is necessary simply to draw the handle 43 down. This will move the head into coacting relation with the buck, develop a pressing reaction whose intensity is determined by adjustment of the wheel 32, and lock the press in closed position because the secondary toggle links 46 move past center. To open the press it is necessary merely to force the handle 43 upward.

Thus the manipulation is extremely simple and, at the same time, the linkage is such as to develop the necessary high pressure. This high pressure arises from the fact that motion of the secondary toggle to locked position, as above described, swings the lever 34 counter-clockwise and brings the pivot 35 connecting the two elements of the primary toggle very close to the straight line connecting the centers of the pivots 26 and 37. A single operating member or handle in a conveniently accessible location serves to open and close the press, and to lock and unlock it, and assures proper sequence of operation without any thought on the part of the operator. The device is inexpensive to construct, light as compared to the foot operated presses common in the prior art, and very attractive from the manipulative standpoint because of the single throw of the actuating handle 43, both in the opening and in the closing movements of the press.

While one embodiment of the press has been described in considerable detail, this is intended to be illustrative and not limiting and modifications within the scope of the claims are contemplated.

I claim:

1. The combination of a support, a buck carried thereby; a lever pivoted on said support; a head carried by said lever into and out of pressing engagement with said buck; a toggle linkage interposed between said support and a portion of said lever and permanently hinged to each; a second toggle linkage reacting between said lever and a component of the first toggle linkage to actuate the lever throughout its entire range of movement; and an actuating handle moving with a component of the second toggle linkage.

2. The combination of a support; a buck carried thereby; a lever pivoted intermediate its ends on said support and extending forward and rearward from such pivot; a head carried by said lever at the forward end thereof and shiftable by motion of the lever into and out of pressing engagement with said buck; a pair of strut toggle links hinged together, one journaled on the support and the other journaled on a member moving with the rear end of said lever, the latter link having a portion extending beyond the last named journal; a tension member hinged to said extending portion and extending forward along said lever over said head; a handle carried by the forward portion of said tension member; and strut guide links pivoted to said lever and to said tension member and forming therewith a locking toggle.

3. In a garment press, the combination of a support; a buck carried thereby; a lever pivoted on said support; a head carried by said lever into and out of pressing engagement with said buck; a toggle linkage interposed between said lever and a portion of said support, the linkage when approximately straightened serving to hold said head in pressing engagement with said buck; an actuating link connected with a portion of said toggle linkage; a guide link short as compared with the actuating link, and pivoted to said lever and to said actuating link, the actuating link and the guide link together forming a secondary toggle in which both links swing in arcs generally consonant with each other and with the path of the head-carrying portion of the lever; and a handle mounted on said actuating link.

4. The combination of a support having a buck mounted thereon; a lever pivoted between its ends on said support; a head carried by the forward end of said lever, into and out of pressing engagement with said buck; a toggle linkage interposed between said support and the rear end of said lever; combined force-multiplying and locking means comprising an actuator member hinged to said toggle linkage and extending therefrom forward along said lever at least to the forward end of the lever, and a relatively short guiding toggle link hinged to said actuating member and to the lever adjacent the head; and a handle carried by said force multiplying and locking means near the forward end of the actuating member, said handle having a single continuus throw to close the press, develop the pressing force and lock the press.

WILLIAM STROBRIDGE.
